UNITED STATES PATENT OFFICE

CLEMENT F. STREET, OF GREENWICH, CONNECTICUT, ASSIGNOR TO AMERICAN STEEL FOUNDRIES, OF CHICAGO, ILLINOIS, A CORPORATION OF NEW JERSEY

GRATE

Application filed February 21, 1929. Serial No. 341,685.

This invention pertains to grates, and more particularly to the dumping or rocking type or to the fixed type of multiple section grates used for locomotives.

There are special requirements for grates to be used in locomotive service, which are peculiar to that service alone and which must be constantly borne in mind to produce successful devices. One is that the grates must be of sufficient width to allow rapid cleaning of the fire. Another requirement is that they must be so constructed as to allow those changes necessary to permit the passage of the proper amount of air through the grates, as well as to so support the assemblies that in operation they will always remain in certain relative positions with respect to each other.

Due to the intense heat to which grates are subjected, the bars thereof are of course liable to rapid deterioration due to burning out. Trouble is also encountered due to warping or twisting in expansion or contraction of the grate bars. This means that the grate bars must be easily accessible and readily removable to allow rapid repairs, because it will be easily understood that the demurrage charges on locomotives are enormous.

The more satisfactory grates now in use are quite expensive to install and maintain as they are usually made up of a great number of small parts, which parts per se become distorted, making it necessary to replace or repair a plurality of them. This is expensive due to the cost of the parts, the time necessary to make such repair and the time the locomotive is out of service due to this repair. It will also be appreciated that when one of these parts becomes distorted, it is often impossible to make adjustments in the air opening, which is so necessary to efficient operation.

It is therefore an object of this invention to provide a grate assembly which is inexpensive to build and maintain and one which fulfills all requirements for economic operation and maintenance.

Another object is to provide a grate bar assembly which permits rapid cleaning of the fire and changes of the grate bars.

Still another object is to provide a grate bar assembly which resists distortion, is readily removable and is capable of rapid conversion to provide different drafts to accommodate different fuels.

A still further object is to provide a grate assembly wherein the grate members are secured to their supports by a minimum of parts, yet one which is so constructed that the grate members will be effectively and securely kept in place.

With these and various other objects in view, the invention consists of certain novel features of construction and operation as will be more fully described and particularly pointed out in the specification, drawing and claims appended hereto.

In the drawing, wherein like reference characters are used to designate like parts—

Figure 1 is a top plan view of a grate assembly with one of the grate members removed, dotted lines illustrating the position of said member in operation;

Figure 2 is a longitudinal elevation partly in section of the grate assembly;

Figure 3 is a transverse sectional elevation of the grate assembly, showing one form of locking device;

Figure 4 is a transverse end elevation of the grate assembly; and

Figure 5 is a transverse sectional elevation of the grate assembly, illustrating a modified form of locking device.

The supporting frame 10 of the grate assembly consists essentially of a pair of spaced parallel longitudinal ribs 11, preferably of truss formation and joined at their ends by socket trunnions 12 of either circular or horseshoe type, the longitudinal ribs 11 being joined intermediate their ends by transverse integral ribs 13 of any convenient number, disposed at proper intervals. It has been found highly desirable both from a standpoint of strength and stiffness to form the longitudinal ribs 11 of substantially truss shape, as already described; that is, the longitudinal ribs may be shaped to have their greatest depth adjacent the center thereof to afford the necessary sustaining resistance to the loads to be carried by the

assembly, and in this connection, may or may not be formed with a bottom reinforcing portion, all as particularly shown and described in applicant's application Serial No. 212,739, filed August 13, 1927. The longitudinal ribs are also provided with a suitable number of apertures, depressions or other connections 14 for the application of the usual shaker arms. If, however, the 10 supporting frame is of the fixed type, the connections 14 may of course be omitted, but such structure, it will readily be perceived, will in no way affect the objects or purposes of this invention.

15 Any number of grate plates 15 may be provided to complete the grate assembly, the number of course depending upon the length of the assembly to be used, and it will be understood that if a short assembly 20 is to be used, only one plate may be necessary but in the usual locomotive assembly, two or more plates are preferably provided. The plates 15 may be either of the arcuate or flat type and provided with a predetermined number of spaced holes or apertures 25 16 of a size to accommodate proper combustion of the fuel for which the plate is designed. These apertures are located inwardly of transversely and longitudinally disposed depending flanges 17 and 18, the end flanges adjacent the trunnions being of such a depth or such a disposition as to provide a seat 118 for the grate on the socket trunnion 12, as particularly shown in the 30 right-hand portion of Figure 2. The opposite transverse flange; that is, the one adjacent the center of the assembly, as shown in Figure 2, is of sufficient depth or disposition to provide seats 218 on the longitudinal ribs 11, said flange being provided preferably on the outside of said ribs, with depending lugs 20 disposed adjacent the ribs 11 and are for the purpose of cooperating with securing means to be later described to keep the plates 35 in place with respect to the supporting means.

The grate plates may also be provided with depending local securing lugs 21 disposed intermediate the ends of the grate and adjacent longitudinal ribs 11. In the modification illustrated in Figure 3, these lugs are provided with aligned apertures 22 registering with aligned apertures 23 provided in the longitudinally extending ribs 11 for the purpose of accommodating a locking member 24, which member may take the form of a headed bar provided with a keyway 25 adapted to receive the locking pin 26 for maintaining said bar in position.

60 With such construction, it will be seen that the grates are fixed to the supporting ribs at points aligned transversely of the assembly, permitting expansion and contraction of the assembly, the lugs 20 serving as guiding means permitting said expansion and

contraction of the inner end of the grate plate, yet at the same time preventing warping, twisting or displacement of the plate transversely of the assembly.

70 The assembly may be varied somewhat as illustrated in the modification shown in Figure 5, by providing the grate plate with the depending lug 30, said lug being provided with an inwardly extending pin 31 adapted to be positioned and retained in the aperture 23 provided in the longitudinal rib 11, it being understood of course that the lug 31 may be disposed on the rib 11 and positioned in an aperture corresponding to the aperture 22. The grate plate 115 may also be provided with a depending lug 32, said lug being provided with an aperture 33 registering with aperture 23 in the opposite rib 11, and in such case, a short headed locking bar 34 may be provided having the keyway 35 for accommodating the locking key 36, a shim or liner 37 being provided between the locking pin and the lug 32, if desired, for the purpose of taking up the wear between said parts.

80 It will be seen that with the constructions illustrated and described that the grate assembly may be easily taken down, changed or repaired, it being only necessary to move the locking pins from their respective locking bars and remove said bars, in which case the plates may be lifted off from the supporting frames and repaired or replaced.

85 It is to be understood that I do not wish to be limited by the exact embodiment of the device shown, which is merely by way of illustration and not limitation, as various and other forms of the device will of course be apparent to those skilled in the art.

90 I claim:

1. In a grate assembly, the combination of a support including spaced members, a grate member carried by said support, said grate member being provided with depending members, securing means for fastening said depending members to said spaced members, and other depending members provided on said grate member and disposed in cooperative relation to said spaced members whereby said grate member is positioned thereon.

105 2. In a grate assembly, the combination of a support including spaced parallel members, a grate member provided with depending end portions contacting with and supported by said support, removable means intermediate said depending portions for securing said grate member to said support, and depending portions on one of said depending end portions cooperating with said parallel members for preventing displacement of said grate member.

110 3. In a grate assembly, the combination of a support including spaced parallel members, a grate member provided with depending end portions contacting with and supported by said support, aligned depending securing

lugs on said grate member provided with apertures registering with aligned apertures on said parallel members, removable locking means extending through said apertures for
5 securing said grate member to said support, and depending portions on one of said depending end portions cooperating with said parallel members for preventing displacement of said grate member, transversely of
10 the parallel members.

Signed at Chicago, Illinois, this 14th day
of February, 1929.
